TRENCH HOE

Ralph H. Slater, Duluth, Minn.

Application September 4, 1953, Serial No. 378,513

4 Claims. (Cl. 214—138)

This invention relates to trench hoes, which are also called pull-shovels or back-diggers, and has special reference to an improved boom-stick-pitch brace relationship.

Trench hoes have been in use for several years, having been originally intended for digging ditches where material or dirt excavated from the ditches is piled up alongside of the ditch for return into the ditch later. Trench hoes work very well in this capacity. However in late years, the trench hoe is being used more and more in digging operations where material excavated must be loaded on trucks or the like and hauled away. Some of these operations are basement digging, and trench digging, where a gravel or other special fill is required for the excavation.

Trench hoes are not very efficient when it comes to loading because of the fixed angle of the bucket relative to the stick. Loose granular or wet material spill from the bucket after it is raised far enough to clear the truck box to dump, and as soon as the bucket is pushed outwardly so that only a part of the load picked up gets into the truck, requiring more scooping operations to fill the truck. Obviously this wasted effort is expensive. However, it is still less expensive to use a trench hoe for many types of digging operations because a trench hoe can dig a hole without getting into the hole, as is necessary with a power shovel.

It is therefore one of the principal objects of my invention to provide means for increasing the efficiency of a trench hoe when loading trucks, and substantially eliminating spillage.

Another object is to provide for increased efficiency in a trench hoe's digging operation.

A more specific object of my invention is to provide an improved mounting relationship between a trench hoe bucket, stick, and pitch brace whereby the angle of the bucket relative to the stick is progressively varied as the stick moves forwardly and rearwardly during its operation.

Another object is to pivotally mount a trench hoe bucket on the lower end of the stick, and to provide a pair of spaced pitch braces which are pivotally mounted on the bucket in spaced relation to its mounting on the stick, the pitch braces being pivotally connected at their opposite ends to the boom in spaced relation to the pivotal mounting of the stick on the boom and on the opposite side of the stick whereby the pitch braces cross the stick.

These and other objects and advantages of my invention will become more apparent as the description proceeds.

In the accompanying drawing forming a part of this application:

Fig. 1 is a top plan view of the outer end of a trench hoe boom showing my invention.

Fig. 2 is a side elevational view of the boom and stick of a trench hoe showing my improved bucket and pitch brace mounting in full lines at the start of a digging

2

cycle and comparing same with a conventional trench hoe shown in dotted lines.

Fig. 3 is a view similar to Fig. 2 showing the end of the digging cycle.

Fig. 4 is a view similar to Fig. 3 showing a modified form of my invention wherein the lower ends pitch braces are attached to the forward end of the bucket and the stick is attached to the rear end of the bucket. Likewise the attachment of the upper ends of the pitch braces and the stick to the boom are reversed.

Fig. 5 is a side elevational view of a trench hoe equipped in accordance with my invention and showing the digging cycle in dotted lines.

In the drawing, the reference numeral 1 indicates the cab or body of a trench hoe to which the boom 2 is pivotally attached at its lower end, all of which is conventional in a conventional trench hoe, the stick 3 is pivotally mounted on the outer end 4 of the boom 2 by means of a suitable pin 5. A cable 6 is connected to an extension 7 of the stick and is operated by conventional means, not shown, within the cab 1 of the trench hoe to pivot the stick so as to force the lower, or outer end 8 of the stick outwardly, or away from the cab 1. A second cable 9 is attached to the lower end 8 of the stick and is carried over a suitable pulley or sheave 10, rotatably carried on the boom 2, to pull the lower end of the stick inwardly, or towards, the cab 1. This arrangement is conventional, and the trench hoe operated by operating suitable controls within the cab can pivot the stick on the boom as required for its digging. In a conventional trench hoe the boom 2 is provided with suitable means, not shown, whereby the outer end 4 of the boom may be raised and lowered for digging and discharging operations.

In my invention the bucket 11 is pivotally mounted on the lower end of the stick 3 by means of suitable spaced lugs 12—12 and a pin 13 extending through the lugs 12 and the lower end of the stick. This provides a pivotal mounting for the bucket on the stick, and as shown in Figures 1 and 2, the stick is pivotally mounted adjacent the lip, or leading edge end of the bucket, while in Fig. 4 the stick is shown as being attached to the trailing edge of the bucket. This arrangement differs from conventional bucket mountings in that there is no pivoting of the bucket relative to the stick in a conventional trench hoe.

In my device I provide a pair of pitch braces 14—14, one of which is pivotally mounted on each side of the boom by a common mounting pin 15 which extends through the boom and pivotally carries each of the pitch braces 14 at their upper ends. The pitch braces are carried in lateral alinement with each other, and have their lower ends pivotally carried by suitable mounting lugs 16—16, and pins 17 extending through the lugs and the lower ends of the pitch braces. The lower ends of the pitch braces are pivotally mounted on the bucket in spaced relation to the pivotal mounting of the stick to the bucket. In Figs. 2 and 3 the lower ends of the pitch braces are carried adjacent the trailing edge of the bucket, while in Fig. 4 the lower end of the pitch braces are carried adjacent to the forward end of the bucket. The upper ends of the pitch braces in Figs. 2 and 3 are pivotally mounted in rearwardly spaced relation to pivot pin 5 of the stick. In Fig. 4 the upper ends of the pitch braces are carried by an extension 18 of the boom, said extension being forwardly of the pivot pin 5 of the stick.

It is thus deemed apparent that the pitch braces and the stick, are crossed.

The crossing of the pitch braces with the stick differs from the conventional trench hoe wherein the pitch braces 19 are carried and secured between the bucket and the boom directly to the stick itself, thus providing a rigid

and fixed angular relation between the stick and the bucket. In the present invention the angle of disposition between the bucket and the stick varies as the stick is moved forwardly and rearwardly. The drawings clearly illustrate in solid lines the relative positions of the bucket during the digging cycle when the present invention is employed and in dotted lines the positions taken by a conventionally mounted bucket.

In Fig. 3 it can be readily seen that when the boom has been raised and the stick pulled inwardly as when the bucket is fully loaded, the bucket cradles its load so that the stick can be pulled outwardly at a considerable distance to where it can be emptied into the body of a truck very completely. Less lineal distance is required to make it dump all the material from the bucket because of the rapidly changing angle of the bucket due to the pitch brace installation. It is deemed readily apparent that the bucket when held in the position shown in Fig. 3 will not discharge, or lose any of its contents until it has reached the inclination in which the conventional bucket would be carried as at 23. It will take a substantial forward or outward moving of the stick 3 to pivot the bucket to the position shown at 23, where it might lose some of its material. Whereas in the conventional installation the bucket begins losing and spilling material practically as soon as the stick is moved forwardly and outwardly, or dumping into the truck.

It is deemed apparent that a trench hoe equipped in accordance with this invention will be more readily capable of picking up and dumping a full bucket with each digging cycle, than will a conventional trench hoe, especially when loading trucks or other vehicles where the points of dumping are substantially above the ground level.

In Fig. 4 the pitch braces cross the stick, and the operation of the device is similar to that of Figs. 2 and 3. However, in the modified form of the invention, the stick is pivotally mounted adjacent the trailing edge of the bucket, and the pitch braces are pivotally mounted adjacent the lip edge of the bucket. The crossing of the pitch braces and the stick makes it necessary to add an extension 18 to the boom beyond the pivot point 5 of the stick, the pitch braces being pivotally mounted adjacent the outer end of extension 18, beyond the pivot point of the stick.

As shown in the drawings suitably spaced openings 24 may be provided on the pitch braces and/or the boom, whereby the angle of attack of the bucket may be regulated as desired to accommodate varying digging requirements. It is deemed apparent that the advantages of the cross pitch braces and stick, whereby the angle of the bucket is progressively varied as the digging cycle proceeds, will be maintained even though the adjustment feature is employed.

Having thus described my invention, what I claim is:

1. In a trench hoe machine for excavating material having a boom, the combination of a dipper stick pivotally mounted intermediate the ends thereof to the end portion of said boom for pivotal movement about a horizontal axis, cable means connected to said stick adjacent the opposite ends thereof for pivotally moving said stick alternately in opposite directions about the horizontal axis, a bucket pivotally mounted adjacent the leading end thereof to the lower end of said stick, and a longitudinally extending brace pivotally mounted at one end thereof to said bucket adjacent the trailing end thereof, said brace at the opposite end being pivotally secured to said boom in inwardly spaced relation to the mounting of said dipper stick on said boom.

5 15 2. The structure defined in claim 1, wherein said brace is adjustably secured to said boom and selectively mountable thereto in a plurality of longitudinally spaced positions therealong for adjusting the variation of the angle of attack of the bucket throughout the digging cycle 20 thereof.

25 3. In a machine of the type described for excavating material having a boom, a dipper stick pivotally mounted intermediate the ends thereof to said boom, means connected to said dipper stick adjacent the opposite ends thereof for pivotally moving said dipper stick in opposite directions about a horizontal axis, a bucket pivotally mounted adjacent the leading end thereof to the lower end of the dipper stick, and a brace means pivotally mounted at one end thereof to the bucket adjacent the trailing end thereof, said brace means having the opposite end pivotally secured to the boom in inwardly spaced relation to the pivotal mounting of the dipper stick on the boom.

4. A trench hoe machine for excavating material, said 35 machine comprising, in combination, a boom, a dipper stick pivotally mounted intermediate the ends thereof to the end portion of said boom for pivotal movement about a horizontal axis, means connected to said dipper stick adjacent the opposite ends thereof for pivotally moving said dipper stick in opposite directions about the horizontal axis, a bucket pivotally mounted adjacent the leading edge thereof to the lower end of said dipper stick, and a pair of elongated pitch braces each being pivotally mounted at one end to said bucket adjacent the trailing edge thereof, each of said braces being pivotally secured at the opposite ends, respectively, to the boom in inwardly spaced relation to the mounting of the dipper stick on the boom.
